United States Patent Office.

DAVID R. KLINE, OF ALLEN TOWN, PENNSYLVANIA.

Letters Patent No. 99,325, dated February 1, 1870.

IMPROVED SASH-HOLDER.

The Schedule referred to in these Letters Patent and making part of the same.

To all whom it may concern:

Be it known that I, DAVID R. KLINE, of Allentown, in the county of Lehigh, and State of Pennsylvania, have invented an Improved Sash-Lock; and I do hereby declare that the following is a full, clear, and exact description of the same, reference being had to the accompanying sheet of drawings, and to the letters of reference marked thereon.

My invention consists of a sash-lock, in which an eccentric or toe-cam, which projects downwardly from a sliding lever, a longitudinal slot of the lever, and a recess or opening in the case or frame of the window, are employed to retain the sash at any degree of elevation or opening, and to lock it when down.

On reference to the accompanying sheet of drawings, making part of this specification—

Figure 1 is a longitudinal section of a window-frame and sash, showing the sash when closed and locked, and also a supplemental view, showing the sash when raised;

Figure 2 is a sectional view of a detached part of the window-frame and sash, showing the position of the locking-lever when not engaged with the window-frame; and

Figure 3 is an enlarged view of the locking-lever.

Similar letters refer to similar parts in the several views.

The locking-lever A is constructed with an eccentric or cam-foot B, projecting downwardly from it. At the end adjacent to the casing or window-frame, at any convenient part of the body of it, a pin-slot, c, is formed lengthwise, as shown. The outer end is turned upwardly, and forms the thumb-rest or handle f.

An opening, D, is made through one side of the sash E, at any convenient point, the eccentric or cam-end of the lever A takes into it, and is held from working out by a pin, d, on which it slides and vibrates.

When the window is down, and it is required to raise and support it at any particular point, the thumb-end f, of the lever, must be elevated, to clear the eccentric from the frame or case, as shown in fig. 2. When it is at the designated point, as shown in the supplemental view, fig. 1, the thumb-end must be depressed, which causes the cam or foot to engage the frame, and, by forcing the sash against the opposite side of it, sufficient friction is generated to prevent it from falling, by its own gravity. The eccen-

tric or cam holds tighter and more firmly, the greater the downward pressure on the sash.

The sash, when down or closed, is locked, so as not to be raised from without, as follows:

An opening or mortise, g, is formed in the frame F, corresponding, in position, with the lever A. When the sash is at its lowest point, the lever is tilted, as shown in fig. 2, and shoved forward, by reason of the pin-slot c, into the recess or mortise g, the top of that end of the lever engages with the top of the mortise, and the top of the body of the lever bears against the top of the opening D, of the sash. The pin d, in the slot c contributes an upwardly-bearing pressure. In this case the eccentric or cam does no come into play.

It will be seen, from fig. 1, and its supplemental view, and fig. 2, that the top of the opening D, of the sash E, is bevelled upwardly, outwardly and inwardly. The outwardly-inclined bevel is to assist the lock in holding the sash open or raised, as shown in the supplemental view of fig. 1, by giving it an inclined bearing, thereby permitting the swell of the cam to more fully contact or press against the frame or casing of the window. The inwardly-inclined bevel assists the lock in holding the sash down or closed, as shown in fig. 1.

The lever A has two downwardly-bearing pressures, viz, the top of the opening in the casing of the window, and the inwardly-inclined bevel of the opening D, of the sash, and one upwardly-bearing, viz, the pin d.

I am aware that a cam or eccentric has been heretofore used for sash-locks, and is therefore not the subject of a patent, in itself, being an old device. I am also aware that a cam, moving on a pin, in a slot, is not new.

What I claim as my invention, and desire to secure by Letters Patent, is—

The lever A, with its cam or eccentric B, and slot c, in combination with the pin d, the opening D of the sash, with its double inclines or bevels, and the mortise g, in the case or frame of the window, substantially as shown and described.

In testimony whereof, I hereunto sign my name to this specification, in presence of two subscribing witnesses.
